UNITED STATES PATENT OFFICE.

WILLIAM JOHN GOULD, OF BARRASFORD, NORTHUMBERLAND, ENGLAND.

EGG BEATER AND THE LIKE.

Application filed March 16, 1928, Serial No. 262,278, and in Great Britain October 11, 1927.

This invention relates to egg beaters and the like and has for its object to provide such devices of an extremely simple character, cheap to manufacture and efficient in use.

5 In general, egg beaters constructed according to the invention comprise a frame or what may be termed a "needle" having any desired number of arms radiating from a central portion. The central portion is adapted 10 to be attached to any suitable device by which the frame may be rotated about the centre and in its own plane. The arms are formed or provided with a number of apertures in desired positions and between the arms a 15 thread or threads of suitable material, such as cotton, silk, linen thread, fine wire of suitable metal, or otherwise are adapted to be threaded through and by means of the apertures, and suitably retained in position.

20 In this manner when the frame with the threads extending between the arms is passed below the surface of the liquid or the like, upon rotating the device by which it is carried, the frame and the threads are caused 25 to move within the liquid and by their action to intimately mix and subdivide it.

One particular form of device constructed according to the invention comprises a frame or needle portion formed of thin sheet metal, 30 preferably steel, and having three radial arms or blades of equal length and spaced at equi-angular distances apart. These blades towards the ends and in an intermediate position are formed with suitable apertures and between the apertures a strand of suitable material is threaded and retained 35 in position in any desired manner. The central portion of the frame or needle is adapted to be attached to a shank, which in turn 40 can be disposed in the chuck of a device resembling a small Archimedean drill or to the end of what may be termed a rolling stick. By this means the device can be rotated and caused to effect the mixing.

45 In order that the invention may be better understood, it will now be described with reference to the accompanying drawings which shew a preferred embodiment and in which:—

50 Fig. 1 is a plan view of the frame or needle.

Fig. 2 is a similar view to Fig. 1 but with the strand of suitable material threaded through the various apertures and retained in position by suitable means.

55 Fig. 3 shews to a smaller scale a somewhat diagrammatic side elevation of a frame or

needle as shewn in Figs. 1 and 2 attached to one end of a rolling stick.

Fig. 4 is a similar view to Fig. 3 but shewing the frame or needle with a shank attached thereto adapted to be used in conjunction with an Archimedean drill or the like.

As will be seen from Figs. 1 and 2, the frame or needle comprises three arms *a*, *b* and *c* radiating from a central portion *d*. 65 This frame is formed from sheet steel or other suitable metal, preferably stamped out, and the arms *a*, *b* and *c* are of equal length and spaced at equi-angular distances apart. *e*, *f* and *g* are holes or apertures in the arms 70 *a*, *b* and *c* towards the ends thereof, whilst *h*, *j* and *k* are similar holes in intermediate positions along the lengths of the arms *a*, *b* and *c*. *m* is a perforation in the central portion *d*. *n* is a thread of cotton, silk, linen, 75 fine wire or otherwise. One end of this thread is passed through the hole *e* in the arm *a* and knotted thereto. By means of an ordinary sewing needle or the like the thread is now passed through the hole *f* to the hole 80 *g* and thence back to *e*. To taunt the thread and to slightly bend the blades *a*, *b* and *c* into shallow arcs, the thread is now slightly pulled and attached to the arm *a* by means of the aperture *e* by a slip knot or otherwise. The 85 thread is now passed through the hole *h*, through the hole *j*, through the hole *k* back to *h*. From *h* it passes to *j*, from *f* to *k*, from *k* to *e*, from *e* to *j*, from *j* to *g*, from *g* to *h*, 90 where it is knotted off.

In using the device the frame or needle is attached in some cases to one end of a rolling stick such as *p*, Fig. 3, by means of a suitable screw or the like *s* which passes through the aperture *m*. In other cases, for example as shewn in Fig. 4, a shank such as *t* is riveted to the frame or needle by means of the aperture *m*. In this case the said shank can be used instead of a drill in an ordinary Archimedean drill, for example of the type comprising a stem having a thread of sudden pitch, which stem carries a chuck and has rotatably mounted at one end thereof a handle, and mounted to slide thereon a nut device. By holding the handle in one hand and reciprocating the nut device up and down on the stem, the stem is caused to rotate first in one direction and then in the other, and this rotation is imparted to the frame or needle carrying the threads, which should be disposed beneath the surface of the liquid or the like to be beaten or mixed.

In the case such as illustrated in Fig. 3, the rotation is effected by rolling the stick *p* between the palms of the two hands of the user.

5 What I claim and desire to secure by Letters Patent of the United States of America is:—

10 1. An egg beater comprising a frame of stiff sheet material having a central portion and a number of arms radiating therefrom so that the central portion and arms come substantially in the same plane, means attached to the central portion by which a rota-

tion may be imparted to the frame around an axis at right angles to the plane of the frame, and a thread stretched in straight portions between the radial arms in various positions.

15 2. An egg beater as claimed in claim 1, in which the radial arms are provided with perforations through which the thread passes.

3. An egg beater as claimed in claim 1, in which the frame is formed from a stamping of sheet metal.

In witness whereof I affix my signature.

WILLIAM JOHN GOUNDRY.
